UNITED STATES PATENT OFFICE.

FELIX Q. RAST, OF NEW YORK, N. Y.

PAPER-HOLDING DEVICE.

Application filed May 11, 1923. Serial No. 638,263.

To all whom it may concern:

Be it known that I, FELIX Q. RAST, a citizen of the United States, residing at New York city, county of New York, borough of Manhattan, and State of New York, have invented new and useful Improvements in Paper-Holding Devices, of which the following is a full, clear, and exact specification.

10 My invention relates to devices for supporting rolls of paper and refers particularly to devices comprising locking means for protecting the roll from removal while allowing the paper to be removed from the roll in predetermined lengths.

15 For particular uses, it is desirable to have paper in the form of rolls, preferably supported to allow of the revolution of the roll, in order that the paper may be readily removed therefrom.

20 In some specific cases of paper employment, it is desirable that paper strips of predetermined lengths may be readily removed from the roll, and further, when 25 rolls of this character are exposed in public places, it is advantageous that some means be employed whereby the theft, or removal, of the paper roll may be prevented.

20 The device of my invention possesses all 30 of the above described desirable attributes with other features of novelty and usefulness as will be evident upon a consideration of the accompanying drawings and my description thereof.

35 My invention comprises a device suitable for the holding of a roll of paper in such a manner that it can not be removed therefrom until all of the paper has been removed from the core. The locking device 40 is simple in construction, positive in action and incapable of being unlocked while the paper roll is within the device.

45 The device of my invention possesses also the valuable property of allowing of the removal of a predetermined length of paper, the severance of the paper at the desired line being accomplished by the interruption of the revolution of the roll at predetermined periods of roll revolution, the 50 removal of the length of paper allowing the return of the roll into its normal position for reuse.

55 A further valuable feature of the device of my invention is that the roll-revolving means is of such a character as to be oper-

ative only with roll cores of certain predetermined forms, thus assuring the purchaser of the source of his paper and enabling the manufacturer, or seller, of the device to be protected against the substitution of inferior paper.

60 My device is simple in construction, compact in form, economical in production and efficient and positive in operation.

65 In the particular form of a device of my invention, shown in the accompanying drawings, similar parts are designated by similar numerals.

70 Figure 1 is a top plan view of one form of the device of my invention with a paper roll in position.

75 Figure 2 is a front view of Figure 1 with the paper roll omitted.

Figure 3 is a broken cross-section through the line 3—3 of Figure 1.

75 Figure 4 is a cross-section through the line 4—4 of Figure 3.

Figure 5 is a cross-section through the line 5—5 of Figure 3.

80 Figure 6 is an end view of a paper roll showing opening for sleeve.

85 Figure 7 is a view of the other end of the paper roll showing opening for revolving means.

90 The particular form of the device of my invention, shown in the accompanying drawings, comprises a support having the ribbed arms 10 and 11, the angular portions 12 and 13 of which are riveted to the back 14 by means of a plurality of bolts 15, 15. Within the back 14 are two spaced slots 16, 16 to allow of the insertion of the screws 17, 17 whereby the support may be affixed to a wall 18.

95 The arm 10 is extended into the hollow lock-carrying cylindrical member, or casing, 19 having the hollow pin-carrying cylindrical member 20 connected therewith.

100 Slidable within the lock-carrying member 19 is a sleeve 21 having the expanded head 22. The sleeve 21 has an opening 23 in alignment with the interior chamber of the pin-carrying member 20 when the sleeve is in its furthermost inward position.

105 Slidable within the sleeve 21 is a bolt having a flange 24, a restricted portion 25, an inclined portion 26, a body portion 27, a restricted portion 28 and a head portion 29. The portions 24, 27 and 29 abut upon the inner face of the sleeve bore and the por-

tion 25 is in alignment with the opening 23 and the opening in the member 20. A spiral spring 37 tends to move the bolt outwardly of the sleeve, the movement being limited by the pin 30 passing through the sleeve 21 abutting upon the bolt member 27.

Positioned within the chamber 31 of the member 20 and the opening 23 of the sleeve 21 are a pin 32 and a driver 33, a spiral 10 spring 34 tending to force the driver 33 inwardly toward the sleeve, the pin 32 resting upon the bolt portion 25.

When the device is in normal position, as shown in Figure 1, the sleeve 21 is locked 15 from movement within the lock-carrying cylindrical member 19 as the driver 33 extends between the chamber 31 and the opening 23. As the bolt is pushed inwardly, the pin 32 rides up the inclined bolt member 26, 20 forcing the driver into the chamber 31, the inward movement of the bolt being limited by the abutment of the pin 30 upon the bolt member 29. When the bolt is in this inward position, the top of the pin 32 is flush with 25 the face of the sleeve 21, the driver being thus moved from engagement with the member 19 and the sleeve 21, thus allowing the latter to be moved outwardly of the member 19, the movement being limited by the abutment of the sleeve pin 35 upon the inwardly 30 extended pin 36 of the member 19. During this movement of the sleeve, the driver 33 slides along the bolt member 27.

This sleeve movement allows the inwardly 35 extended portion of the sleeve to be withdrawn into the member 19, for purposes described later.

When the sleeve is returned to its former 40 position within the member 19, the driver 33 is forced by the spring 34 into locking position preventing the movement of the sleeve.

The arm 11 carries a core-holding member comprising a blade, or elongated revolving member, 38, the annular arm-abutting member 39 and the shaft 40 which passes through an opening in the arm 11 and is carried revolvably therein. A spiral spring 41, fixedly attached to the shaft 40 and the outer face of the arm 11, tends to maintain tensioned abutment between the pin 42 of the member 39 and the pin 43 of the arm 11.

The movement of the core-holder against the tension of the spring 41 is limited by 55 the abutment of the pin 42 upon the member 44, which is integral with the inner face of the arm 11.

A cover 45 is attached to the arm 11 by means of a plurality of screws 46, 46, the screw 47 acting as a support for the outer end of the shaft 40.

The shaft 21 and the core-support member 39 are in alignment with each other.

The core suitable for use in my device, 65 and around which paper 52 is wound, com-

prises a closed cylindrical member 48, preferably of cardboard, one end of which 53 has an opening 49 capable of receiving the end 50 of the sleeve 21, and the other end of which 54 has an elongated opening 51 capable of receiving the elongated member 38.

The operation of my device is as follows, assuming it to be empty.

The bolt head 29 is pushed inwardly thus 75 unlocking the sleeve 21 and allowing it to be pulled outwardly by means of the sleeve head 22. A paper rolled core of the described character is then positioned between the extremities of the arms 10 and 12, the elongated revolving member 38 being inserted within the opening 51 of the end 54 of the core. The sleeve is then pushed inwardly positioning the inward end of the sleeve within the opening 49 of the end 53 of the core. When this position is reached, the driver 33 locks the sleeve from further movement. The roll of paper is thus locked in position, one end of the core being supported by the revolving member 38 and the other end of the core being supported by the member 50 of the sleeve around which it is readily revolvable.

To remove the paper, it is pulled, revolving the roll until the pin 42 of the member 39 abuts upon the stop member 44 of the arm 11 when further revolution is impossible. An increased, or continued, pull upon the paper will tear it, preferably upon predetermined lines, and the roll thus released 95 will return to its former position by means of the spring 41.

A consideration of the drawings and my description will show that the core can not be removed from retention in the device until all of the paper has been removed therefrom. When the paper has been removed from the core, the core may be cut, or broken, allowing it to be removed and a new paper-rolled core may be introduced as described above.

The revolving member 38 and the core opening 51 need not be of the particular shape shown, as their co-ordination is for the purpose of both holding the core and returning it to its normal position when released from a revolved position, and hence, wide variations may be made without going beyond the scope of their purpose and utility.

It will thus be seen that the device of my invention is directed toward the removal of a definite predetermined length of paper from a roll and is of such construction that a roll of paper cannot be removed therefrom, that the bare core of a paper roll can be easily removed therefrom and that a new roll of paper can be readily introduced and locked in revolvable position.

I do not limit myself to the particular size, shape, number or arrangement of parts,

as shown and described, as these are given simply as a means for clearly explaining the device of my invention.

What I claim is:

- 5 1. In a device for revolvably holding a roll of paper, in combination, a support, a pair of parallel arms fixedly attached to the support, a revolvable member having an extended angular element capable of insertion 10 within a correspondingly formed opening within the end of a roll core and revolvably therewith, said revolvable member being carried by one of the arms, a slideable extended member in alignment with the angular member 15 capable of revolvably holding the core when in locked extended position, said slideable member being carried by the outer arm, a locking means, means positioned within the core for unlocking the slideable member 20 allowing its movement to disengage said member from said core, means for limiting the revolvable movement and spring means for returning the revolvable member to its original position from a revolved position.
- 25 2. In a paper-holding device, in combination, a casing having an opening therethrough, a hollow sleeve slideable within the casing opening and extending therethrough, the extended portion being capable of insertion 30 within an opening in a core end, the casing and the sleeve having aligned holes perpendicular to a bolt slideable within the sleeve, a bolt slideable within the sleeve, a driver and a pin within the aligned 35 holes locking the sleeve from movement, means whereby the movement of the bolt will unlock the sleeve, allowing the extended portion of the sleeve to be drawn into the casing, revolving means capable of insertion 40 within an opening in a core end and revolvably therewith and means for maintaining the sleeve and the revolving means in alignment with each other, so spaced that a roll core may be positioned between them when 45 the sleeve is within the casing and be engaged and held by them when the sleeve is withdrawn from the casing.
3. In a paper-holding device, in combination, a frame comprising a back and two 50 spaced arms, a casing having an opening therethrough carried by one arm, a sleeve slideable within the casing and extending outwardly therefrom in the direction of the other arm, means for preventing the withdrawal 55 of the sleeve from within the casing, the casing and the sleeve having aligned holes, a bolt slideable within the sleeve, means for preventing the bolt from withdrawal from the sleeve, a driver and a pin within 60 the aligned holes, the pin resting upon the bolt locking the sleeve from movement with- in the casing, means whereby the movement of the bolt will unlock the sleeve allowing the extended portion to be drawn inwardly towards the casing, means for returning 65 the bolt to its original position with respect to the sleeve, means whereby the return of the sleeve to its original position will lock it from movement, revolvable means carried by the other arm in alignment with the 70 sleeve and means whereby the revolvable means may be inserted within a corresponding opening in the end of a paper roll causing it to revolve therewith, the spacing between the sleeve and the revolving means being such as to allow of the placement of a roll of paper between them when the sleeve is withdrawn and causing the sleeve and the revolving means to engage in openings within the roll ends when the sleeve is in extended position.
4. In a paper-holding device, in combination, a frame comprising a back and two spaced arms, a casing having an opening therethrough carried by one arm, a sleeve 85 slideable within the casing and extending outwardly therefrom in the direction of the other arm, means for preventing the withdrawal of the sleeve from within the casing, the casing and the sleeve having aligned 90 holes, a bolt slideable within the sleeve, means for preventing the bolt from withdrawal from the sleeve, a driver and a pin within the aligned holes, the pin resting upon the bolt locking the sleeve from movement within the casing, means whereby the movement of the bolt will unlock the sleeve allowing the extended portion to be drawn inwardly towards the casing, means for returning the bolt to its original position with 95 respect to the sleeve, means whereby the return of the sleeve to its original position will lock it from movement, revolvable means carried by the other arm in alignment with the sleeve, means for limiting the revolution of the revolving means, means for returning the revolving means to its original position when revolved and means whereby the revolvable means may be inserted within a corresponding opening in the end of a paper roll 100 causing it to revolve therethrough, the spacing between the sleeve and the revolving means being such as to allow of the placement of a roll of paper between them when the sleeve is withdrawn and causing the 105 sleeve and the revolving means to engage in openings within the roll ends when the sleeve is in extended position.

Signed at New York city in the county of New York and State of New York this 30th day of April, 1923.

FELIX Q. RAST.
